UNITED STATES PATENT OFFICE.

DONALD A. QUARLES, OF ENGLEWOOD, NEW JERSEY, ASSIGNOR TO WESTERN ELECTRIC COMPANY, INCORPORATED, OF NEW YORK, N. Y., A CORPORATION OF NEW YORK.

SIGNALING CIRCUITS.

Application filed December 11, 1922. Serial No. 606,057.

To all whom it may concern:

Be it known that I, DONALD A. QUARLES, a citizen of the United States, residing at Englewood, in the county of Bergen, State 5 of New Jersey, have invented certain new and useful Improvements in Signaling Circuits, of which the following is a full, clear, concise, and exact description.

This invention relates to signaling circuits.

An object of this invention is to provide a transmitting and receiving set which may be employed to transmit and receive signals from either a two way signaling 15 circuit or a one-way circuit.

Another object of this invention is to provide an operator's talking and monitoring set which may be employed for talking and monitoring both over a two-wire line 20 and a four-wire line without requiring the main transmission circuit to be broken when the operator's set is in use.

This invention is hereinafter described in detail as embodied in a supervisory circuit for a repeater station at which a four-wire repeater line terminates in a two-wire line. As is well known in the art, two wires of the four-wire circuit are employed for transmission in one direction and the other 25 two wires are employed for transmission in the opposite direction, the four wires being coupled by a suitable transformer arrangement with a two-wire line on which transmission may be had in both directions. 30 One transformer arrangement which may be employed for example, is that disclosed and claimed in the Nyquist application, Serial No. 481,319, filed June 29, 1921 wherein separate transformers may be employed for coupling each side of the four-wire circuit to the two-wire line, a suitable balancing network being employed of course to balance the two-wire line and prevent a local circulation of power from 35 one side of the four-wire circuit to the other.

In accordance with this invention that transformer which is employed for impressing signals from the two-wire line upon one side of the four-wire line is provided with a monitoring winding which may be connected to the operator's transmitter. This additional winding will serve to impress talking currents both upon the outgoing side of the four-wire circuit as well

as upon the outgoing two-wire line. The transformer coupling between the two-wire line and the incoming side of the four-wire circuit is also provided with an additional winding which may be connected in circuit 60 with the operator's receiver whereby monitoring may be added both for messages coming in over the two-wire line as well as those received on the incoming side of the four-wire circuit. This arrangement therefore 65 provides for talking and monitoring in both directions at a terminating station of a four-wire circuit without requiring the main transmission circuit to be broken at any time and without requiring additional 70 transformers.

Referring to the drawing, a terminating four-wire repeater circuit is disclosed therein in which monitoring is obtained by means of this invention.

Line 3 is a two-wire signaling line terminating in an artificial balancing line 4 and inductively coupled to the outgoing side 5 of a four-wire repeater circuit by a transformer 6, and coupled to the incoming side 7 of the said four-wire repeater circuit by another transformer 8.

Line 3 has connected in series therewith a winding 9 of transformer 6, a suitable condenser 10 and a winding 11 of transformer 8. The artificial balancing line 4 has connected in series therewith, a winding 13 of transformer 6, a condenser 14 and a winding 15 of transformer 8. The outgoing side 5 of the four-wire circuit is 90 connected to the winding 16 of transformer 6 while the incoming side 7 of the four-wire circuit is connected to the winding 17 of transformer 8. The impedances of line 3, artificial line 4 and the four-wire circuit 95 may be so related by transformers 6 and 8 that a desired fraction such as one-half of the energy of signaling currents from line 3 will be impressed upon side 7 of the four-wire circuit and the other half will be 100 impressed upon side 5, while none of the incoming energy will be absorbed by the artificial line 4. These impedance relations may also be such that one-half of the incoming energy from side 7 will be impressed upon line 3 and one-half absorbed by artificial line 4, but none of this energy will be impressed upon the outgoing side 5. The above described relation will, therefore, enable satisfactory signaling to 110

take place between line 3 and four-wire circuit since incoming telephone signals, for example, from line 3 by transformer 6, will be impressed upon the outgoing side 5 of the four-wire circuit, amplified by a suitable amplifier 20, and others not shown, whereby the signals from line 3 may be conveyed to any desired distant stations.

Similarly incoming signaling over line 10 section 7 will be amplified by a plurality of repeaters such as the vacuum repeater 21 and by the transformer 8 the amplified signals will be impressed upon line 3 and received by the station connected to the 15 distant end thereof.

Transformers 6 and 8 are provided with the usual transformer cores of some suitable magnetic material on which the various windings may be mounted. That the various 20 windings of the two transformers need not be divided between the two transformers in the manner shown but may be divided in other ways will appear from the Nyquist application above mentioned.

25 In order to provide a talking and monitoring arrangement for the above described circuit this invention provides additional windings 22 and 23 mounted on the core of the transformer 6 so as to be inductive to both the primary windings 9 and 13. Leads 24 and 25 from these windings may be connected through suitable plugs and jacks to an operator's transmitter 26. An operator or supervisor talking into transmitter 26 will cause speech current potentials to be developed in windings 16, 9 and 13 of transformer 6 due to the inductive relations of these windings to the windings 22 and 23. The potential induced thereby 30 in winding 16 will be amplified by repeater 20 and transmitted to the distant station connected to line 5 in the same manner as incoming signaling currents from line 3. Due to the balanced relation above described 35 speech frequency potentials in windings 22 and 23 will develop corresponding potentials in windings 9 and 13, whereby signals from transmitter 26 will be impressed partly on line 3 and on network 4 but none will be absorbed by the side 7 of the four-wire circuit. The transmitter 26 is therefore available 40 for supervisory purposes for talking either with the distant station connected to line 5 or the station connected to the other end of line 3.

In order to monitor those signals coming in over side 7 of the four-wire circuit as well as to monitor incoming signals from line 3 this invention provides additional windings 45 30 and 31 mounted on the core of transformer 8 so as to be inductively related to the other windings of said transformer, and these windings 30 and 31 by suitable leads 33 and 34 and plugs and jacks are connected 50 in circuit with a telephone receiver 35. As

described above one-half of the energy of the incoming signaling current from line 3 is absorbed by the outgoing side 5 of the four-wire circuit, and one-half by the incoming side 7 of the four-wire circuit so that since 79 windings 30 and 31 are inductively associated with windings 11 and 15 in the same manner as winding 17 is associated therewith, it follows that windings 30 and 31 will 75 have developed therein alternating current potentials corresponding to the incoming telephone currents in line 3 whereby monitoring by receiver 35 may take place for telephone currents passing from line 3 to the outgoing side 5. The monitoring windings 30 and 31 will also be responsive to incoming currents from side 7 since these windings are inductively related to winding 17. Receiver 35 may therefore be employed for monitoring telephone currents in either direction while transmitter 26 may be employed for talking purposes in either direction, both the talking and the monitoring taking place without requiring the main transmission circuit to be broken in order 80 to insert in the main line any talking or receiving apparatus or any compensating networks that may be necessary by the connection of such apparatus. The monitoring arrangement on this invention is also 85 inexpensive since no additional transformers are required to connect the transmitter and receiver to the transmission circuit. It is also to be noted that due to network 4 the transmitter 26 and receiver 35 are in anti-side tone relation so that the receiver does 90 not get any of the energy from transmitter 26.

The windings 22 and 23 and 30 and 31 should be so designed that there is the proper matching of impedances between the transmitter and the impedance into which it works and between the incoming circuits for the receiver and the receiver in order to 100 obtain maximum transmission efficiency.

105 It is to be understood that the monitoring and talking arrangement of this invention may be employed in connection with other transformer means for coupling a two-way circuit to two one-way circuits without departing in any wise from the spirit of this invention as defined in the appended claims.

110 The invention claimed is:

115 1. In a signaling system, a two-way transmission line, a one-way transmission line, a second one-way transmission line, an artificial network for balancing said two-way line, transformer means for coupling said lines and said network to render said two way line, said first one way line, said second one way line and said network conjugate, 120 an auxiliary winding on said transformer means coupled to other windings of said means to receive currents from both said two-way line and only the first of said one- 125 130

- way lines, a second auxiliary winding coupled with other windings of said means such that alternating current potentials present in said second auxiliary winding impress 5 currents on said two-way line and only on the second of said one-way lines, local means for indicating signaling currents received by said first auxiliary winding, and local means for impressing signaling currents 10 upon said second auxiliary winding.
2. In a signaling system, a two-way transmission line, two one-way transmission lines, an artificial network for balancing said two-way line, a transformer winding in circuit with said two-way line, a second transformer winding in circuit with said artificial network and inductively coupled to said first winding, a third transformer winding in circuit with one of said one-way lines 15 and inductively coupled to said first and said second windings, a fourth transformer winding inductively coupled to said first three windings, a telephone transmitter connected to said fourth winding, a fifth transformer winding in circuit with said two-way line, a sixth transformer winding in circuit with said network, a seventh transformer winding connected to the other of said one-way lines, an eighth transformer winding 20 inductively coupled to said fifth, sixth and seventh windings, and a telephone receiver connected to said eighth winding.
3. In a signaling system, a two-way transmission line, a one-way transmission line, a second one-way transmission line, an artificial network for balancing said two-way line, a transformer winding in circuit with said two-way line, a second transformer winding in circuit with said network, a third transformer winding connected to said first one-way line, said first and said third windings being mounted on a common core structure, said second winding being 25 coupled to said first one-way line, an auxiliary winding mounted on said core, a telephone transmitter connected to said auxiliary winding, a fourth transformer winding in said circuit with said two-way line, a fifth transformer winding in circuit with said 30 network, a sixth transformer winding connected to said second one-way line, said fourth and said sixth windings being mounted on a common core, an auxiliary winding mounted on said second core, and a telephone receiver connected to said last-mentioned auxiliary winding.
4. A signaling system comprising a two-wire line, an artificial network for balancing said line, a four-wire repeater circuit having 35 a unidirectional path for the transmission 60 of signals in one direction and a second unidirectional path for transmitting the signals in the opposite direction, a transformer for coupling said line to one of said paths, a second transformer for coupling 65 said line to the other of said paths, and an auxiliary winding mounted on each of said transformers, a telephone transmitter connected to one of said auxiliary windings and a telephone receiver connected to the 70 other of said auxiliary windings.
5. A signaling system comprising a two-way transmission line, an artificial network for balancing said line, a four-wire repeater circuit having a unidirectional path for 75 the transmission of signals in one direction and having a second unidirectional path for transmitting the signals in the opposite direction, a transformer having one winding effectively in series with said line and said 80 network and having a second winding connected to one of said paths, a second transformer having one winding connected effectively in series with said line and said network and a second winding connected to 85 the other of said paths, an auxiliary winding mounted on each of said transformers a telephone transmitter connected to one of said auxiliary windings, and a telephone receiver connected to the other of said auxiliary windings.
6. A signaling system comprising a two-way transmission line, an artificial network for balancing said line, a four-wire repeater circuit comprising two unidirectional paths, 90 transformer means for inductively connecting said paths to said line and network, cores of magnetic material for said means, a transmitter, a receiver, and means comprising monitoring windings on said cores for associating said receiver and said transmitter with said repeater circuit, said means arranged to make said receiver anti-side-tone to currents from said transmitter.
7. In combination a two-wire line, a four-wire line, coupled to said two-wire line, a transmitter, a receiver, means for coupling said transmitter to said lines to impress 95 currents upon said two-wire line and on the outgoing side of said four-wire line, means 100 for coupling said receiver to receive currents from said lines, and an artificial network for balancing said two-wire line and for rendering said receiver anti-side-tone.
- In witness whereof, I hereunto subscribe 115 my name this 5th day of December A. D., 1922.

DONALD A. QUARLES.
